UNITED STATES PATENT OFFICE.

WILLIAM HENRY FRANKLIN, OF RED LODGE, MONTANA.

CULVERT.

1,120,471.

Specification of Letters Patent.

Patented Dec. 8, 1914.

Application filed April 23, 1914. Serial No. 823,967.

To all whom it may concern:

Be it known that I, WILLIAM H. FRANKLIN, a citizen of the United States, and a resident of Red Lodge, in the county of Carbon and State of Montana, have invented a new and useful Improvement in Culverts, of which the following is a specification.

My invention is an improvement in culverts, and has for its object to provide a device of the character specified, composed of reinforced cement or plastic material capable of hardening and of sectional form, the sections and the reinforcements being so constructed and arranged that the sections may be rigidly connected together to provide for culverts of various lengths.

In the drawings:—Figure 1 is a side view of a length of culvert composed of sections joined together, Fig. 2 is a front view of one of the end sections, Fig. 3 is a similar view of the other end section, Figs. 4 and 5 are enlarged sections on the lines 4—4 and 5—5, respectively, of Fig. 1, Fig. 4 looking in the direction of the arrows adjacent to the line, and Fig. 6 is a reduced end view of an intermediate section.

The culvert length shown in Fig. 1 is composed of five sections, three intermediate sections and two end sections. Each of the intermediate sections is a frame, consisting of a straight bottom 1 and an arch 2, the arch and the bottom being integral. The openings through the sections 1—2 are of the desired size, and it will be understood that the said sections or blocks may be of any desired size, either as regards the opening or the thickness of the material that encircles the openings. It will be noticed from an inspection of Fig. 1 that the faces of the blocks 1 are not perpendicular to the base, but the said faces are inclined with respect to the base, the faces being of course parallel. The sections or blocks 1—2 may be of any desired length, and as many of these blocks may be used to form the culvert as may be necessary. The end blocks 3 and 4 are rectangular in form, each having the opening 5, corresponding in size to the opening through the blocks 1—2, and the faces of the blocks 3 and 4 are perpendicular to the base.

Each of the blocks 3 and 4 is provided with a rib on its inner face, the rib enclosing the opening and corresponding in shape and thickness to the shape and thick-

ness of the blocks 1—2. The rib 6 of the block 3 is of greatest thickness at the bottom of the block, and at the top of the arch the said rib merges into the adjacent face 60 of the block 3. The rib 7 of the block 4 is oppositely arranged to the rib 6, so far as its thickness is concerned, the rib being of greatest height at the top of the arch and gradually decreasing in height to the bottom of the block when the rib merges into the adjacent face of the block.

The arrangement of the ribs 6 and 7 of the blocks 3 and 4 is such that when the blocks 3 and 4 are placed at the ends of the culvert body formed by the blocks 1—2, the outer faces of the ribs 6 and 7 will fit smoothly against the adjacent ends of the blocks 1—2 when the blocks 3 and 4 stand with their faces perpendicular.

The several sections of the completed culvert are locked together by means of links 8, each block being provided with two links, and the links are arranged at opposite sides of the openings of all the blocks, and at the 80 ribs 6 and 7 in the blocks 3 and 4. Each of the links 8 of the blocks 1—2 extends beyond that face or end of the block which makes an obtuse angle with the base, and the said end of the link is provided with a 85 downwardly depending lug 9. The lugs 9 are spaced from the adjacent face or end of the block, as shown more particularly in Fig. 4, and each of the links inclines slightly upward toward the lug 9.

The links 8 of the block 3 do not extend beyond the outer face of the block, the ends of the links being flush with the said face or within the same. The lugs 9 of the links 8 of the block 4 extend beyond the outer 95 face or end of the rib 7, as shown in Fig. 1, and the opposite end of each link in the block 4 is flush with the face of the block or within the plane of the said face.

In the blocks 1—2 and the block 3 each 100 link 8 is provided at the opposite end from the lug 9 with an eye 10, and each block 1—2 and the block 3 is recessed at the eye as indicated at 11, to receive the eye. The recess is of a depth to receive the eye completely, so that no part of the eye extends beyond the face of the block. The recess 11 of the block 3 is in the rib 6, and the recess is of such depth, that no part of the eye extends beyond the outer face of 110 the rib.

The recesses 11 are of considerable length

vertically, as shown in Figs. 1 and 2, the said recesses extending far enough above the eyes to permit the engagement of the lugs with the eyes and extending far enough below the eyes to prevent engagement of the free ends of the lugs with the lower ends of the recess. The arrangement of the links 8 is such that when the blocks 1-2 are arranged as shown in Fig. 1, the lugs 9 of each block will engage the eyes 10 of the succeeding block, when the ends of the blocks are abutting, thus locking the blocks together in alinement.

The lugs 9 of the block 4 are engaged with the eyes of the adjacent block, and the eyes of the block 1-2 adjacent to the end block 3 are engaged with the lugs of the said block and the arrangement in the blocks 3 and 4 is such that when the links and the lugs are engaged as above specified, the ribs 6 and 7 will fit closely against the adjacent ends of the blocks 1-2. The blocks or sections of the culvert are thus tied firmly together, and it will be evident that when the dirt or other material of the roadway, across which the culvert is laid, is placed over the culvert, the blocks will be held firmly from movement in any direction.

The only manner in which the lugs of any one block may be disengaged from the eyes of the adjacent block is by upward movement of the said block with respect to the adjacent block, and there is no such stress on the blocks when they are in place. The inclined arrangement of the blocks 1-2 has a definite function. After the blocks are laid as shown in Fig. 1 and downward pressure comes upon any one block 1-2, such weight will tend to move the block downward. A portion of the weight is however, carried by the adjacent block toward which the first-named block leans, and the weight is thus uniformly distributed throughout the length of the culvert.

The end blocks support the culvert and provide a neat finish at the ends of the same. It will be obvious that a culvert of any length may be constructed in this manner, the blocks being joined as shown in Fig. 1. In placing the sections together, each block is raised approximately two inches and moved toward the succeeding block to bring the lugs 9 directly above the openings of the eyes. The block is then dropped and as the lugs move into the eyes, the block will be drawn closely into contact with the succeeding block.

In Fig. 5, a preferred method of reinforcement for the individual blocks is shown. It will be noted that two rods or bars 12 are used, the said rods being oppositely arranged and each being bent in opposite directions or in zigzag form, the two rods being embedded in the material of the block. Preferably the rods 12 are provided

with offsets or corrugations at close intervals, and as many pairs of rods arranged as shown in Fig. 5 may be used, as may be desired. In the blocks 1-2 the rods would extend entirely around the blocks, while in the blocks 3 and 4, the rods may be at the rib and at other points if desired. Reinforcing rods arranged in the manner above specified bind the material of the blocks firmly together to resist stress in any direction.

I claim:

1. A culvert composed of intermediate and end sections molded of reinforced plastic material capable of hardening, each intermediate section being a frame having the desired cross section of the culvert, the tops of the intermediate sections being arched, and the planes of the ends of each of the intermediate blocks being parallel and inclined to the plane of the base, each of the end blocks being of rectangular form and adapted to fit against the ends of the culvert and each having a transverse opening having the desired cross section of the culvert, each intermediate block having at each side of the opening a link extending transversely of the block and extending beyond that end whose plane meets the plane of the base at an obtuse angle, the said ends of the links having depending lugs, each link having an eye at the opposite end of the block and each block being recessed to receive the eye, each of the end blocks having a rib on its inner face encircling the opening and of a thickness corresponding to the thickness of the intermediate blocks, the rib of one end section being of greatest depth at its top and gradually decreasing in depth toward the bottom and the rib of the other end section being of greatest depth at the bottom of the block and gradually decreasing in depth toward the top, whereby when the hooks of each block are engaged with the eyes of the preceding block, the inclined faces of the blocks will be drawn tightly together to tighten the blocks of the culvert against each other, the links of the last-named end blocks being at the ribs.

2. A culvert composed of intermediate and end blocks or sections of plastic material capable of hardening, each block having a transverse opening, the intermediate blocks having their ends parallel and inclined to the base, each end block having a rib at its inner face encircling the opening and of a thickness corresponding to the thickness of the intermediate blocks, the rib of one end block being of greatest depth at the top of the block and decreasing toward the bottom and the rib of the other end block being of greatest depth at the bottom and gradually decreasing toward the top, and means for locking the blocks together, said means comprising links ar-

- ranged transversely of the blocks at each side of the opening, each link having at one end a lug and at the other end an eye adapted for engagement by the lugs of the 5 adjacent blocks, the lugs of the links being on that end of the block whose plane meets the plane of the base at an obtuse angle, whereby when the hooks of each block are engaged with the eyes of the preceding 10 block, the inclined faces of the blocks will be drawn tightly together to tighten the blocks of the culvert against each other, and each block being recessed at each eye to receive the eye.
- 15 3. A culvert composed of intermediate and end blocks or sections of plastic material capable of hardening, each block having a transverse opening, the intermediate blocks having their ends parallel and inclined to the base, each end block having a rib at its inner face encircling the opening and of a thickness corresponding to the thickness of the intermediate blocks, the rib of one end block being of greatest depth at 20 the top of the block and decreasing toward the bottom and the rib of the other end block being of greatest depth at the bottom and gradually decreasing toward the top, and means for locking the blocks together.
- 25 4. A sectional culvert of plastic material capable of hardening and comprising intermediate and end blocks or sections, each intermediate section being an open frame and each end section being approximately rectangular in shape, the intermediate sections having the planes of their ends parallel and inclined to the plane of the base, and each end block having a rib encircling the opening and of a thickness corresponding to the 30 thickness of the intermediate block and extending beyond the face of the block to fit against the adjacent end of the adjacent intermediate section when the end block is upright, and means for locking the blocks together. 35
- 40 5. A sectional culvert of plastic material capable of hardening and comprising intermediate and end blocks or sections, each intermediate section being an open frame and each end section being approximately rectangular in shape, the intermediate sections having the planes of their ends parallel and inclined to the plane of the base, and each end block having a rib encircling the opening and of a thickness corresponding to the 45 thickness of the intermediate block and extending beyond the face of the block to fit against the adjacent end of the adjacent intermediate section when the end block is upright, and means for locking the blocks together, said means comprising rods or 50 links arranged transversely of the sections at opposite sides of the opening and having a hook extending beyond that end of the block whose plane meets the plane of the base at an obtuse angle, each link or
- rod having an eye at the other end for engagement by the hooks of the succeeding block, each block being recessed to receive the eyes.
5. A sectional culvert of plastic material 55 capable of hardening and comprising intermediate and end blocks or sections, each intermediate section being an open frame and each end section being approximately rectangular in shape, the intermediate sections 60 having the planes of their ends parallel and inclined to the plane of the base, and each end block having a rib encircling the opening and of a thickness corresponding to the thickness of the intermediate block and extending beyond the face of the block to fit 65 against the adjacent end of the adjacent intermediate section when the end block is upright, and means for locking the blocks together, the movement of the inclined faces 70 of the blocks with respect to each other co-operating with the locking means to press the blocks closely together.
6. In a culvert composed of plastic blocks and of sectional form, intermediate sections, 75 the planes of the sections being parallel and inclined to the plane of the base, means for locking the said blocks together, end blocks for completing the culvert, each end block having a transverse opening, and a rib extending 80 from the face of the block around the opening and abutting and fitting the end of the adjacent intermediate block when the end block is upright, the movement of the inclined faces of the blocks with respect 85 to each other co-operating with the locking means to press the blocks closely together.
7. A culvert composed of blocks and interlocking mechanism for connecting the blocks, the blocks being similar, and each 90 block having its opposite faces parallel and inclined to the plane of the base, whereby when the blocks are laid, the undercut face of each will partially overlie and rest upon the opposite face of the succeeding block. 95
